UNITED STATES PATENT OFFICE.

CLIFTON B. SLOAN, OF KANSAS CITY, MISSOURI.

PROTECTOR-COVER FOR TOILET-CLOSET SEATS.

1,293,955.

Specification of Letters Patent. Patented Feb. 11, 1919.

Application filed September 7, 1916. Serial No. 118,844.

To all whom it may concern:

Be it known that I, CLIFTON B. SLOAN, a citizen of the United States, residing at Kansas City, in the county of Jackson and

5 State of Missouri, have invented a new and useful Improvement in Protector-Covers for Toilet-Closet Seats, of which the following is a specification.

My invention relates to protector covers 10 for toilet closet seats, and the objects of my invention are, first, to provide a cheap, easily made, and portable protector cover which may be folded and assembled into convenient packages suitable for carrying in the 15 pocket or hand bag, second, to provide the protector cover with an inner circular portion adapted to rest upon the ring of the closet seat, and an outer circular portion adapted to fold beneath the inner circular 20 portion and thereby forming shoulders to support the inner portion and to suspend the outer portion, and third, to provide a shield on the inner edge of the inner circular portion at the forward end of the cover, and 25 a projecting portion adapted to fold outwardly of the closet seat and shield its outer edge.

I attain these objects by the means and device illustrated in the accompanying 30 drawing, in which—

Figure 1, is a plan view of my invention;

Fig. 2, is a perspective view of my invention and showing the same in unfolded position and ready to be applied to the closet 35 seat; and

Fig. 3, is a perspective view of my invention in operative position on the seat of the toilet closet and showing the flushing water trapped in the closet bowl in readiness to 40 remove the cover from the seat and draw it into the sewer.

Fig. 4, is a bottom view of the cover, and showing the folding of the loop to provide shoulders.

45 Similar reference numerals refer to corresponding parts throughout the several views.

The numeral 1, indicates a rectangular sheet of paper, which is preferably coated 50 with paraffin or other suitable moisture proof substance. The sheet is large enough to cover the closet seat, including the opening therein. To make my protector cover, the sheet 1, is positioned so that it will appear diamond-shaped, the upper and lower corners of the diamond being in the center

line drawn longitudinally through the closet seat. A cut 2 is made in the sheet in circular direction from a point 3, to a point 4, at the opposite side of the sheet. The cut 60 2 is made to substantially conform with the outer edge of the closet seat, the portion of the sheet outwardly of the cut 2, is thereby formed as and for a depending loop 5, which is adapted to drop into the closet bowl and 65 engage the water trapped therein and in position to be acted upon by the flushing water admitted to the bowl. Inwardly a suitable distance from the cut 2, a cut 6 is made in the sheet and is extended in circular 70 direction from a point 7, to a point 8, directly opposite thereto, thereby forming a shield 9. A cut 10 is made in the sheet in circular direction from a point 11, at the intersection of the cut 6, to a point 12, di- 75 rectly opposite, at the intersection of the cut 6, thereby forming a seat ring 13, and providing the opening 14, which corresponds with the opening in the closet seat. Holes 15 are apertured in the sheet at the 80 terminals of the cut 6, to facilitate the folding of the shield 9, and to prevent the tearing of the cover when the shield 9 is folded on the folding line 16. A folding line 17 is marked in curved line cross-wise the pro- 85 jecting corner 18 of the sheet, to indicate the fold to provide a shield 19, which is adapted to drop outwardly of the forward edge of the closet seat. Folding lines 20 are marked at opposite sides of the sheet, outwardly of 90 the cut 2, to indicate the fold of the loop 5, to provide shoulders 21, adapted to support the seat ring 13, and permit the loop 5, to depend in the closet bowl. The edge of shoulders 21, are shown at 1', in Figs. 1, 95 2, 3, and 4.

My protector cover is applied to the closet seat by folding the loop 5 on the folding lines 20, thereby forming the shoulders 21, and dropping the loop, thus folded, into the 100 closet bowl. This operation brings the seat ring 13, to lie on the ring of the closet seat and to rest on the shoulders 21. The shield 9, is then folded down on the folding line 22, and, thereafter, it covers and protects the 105 inner edge of the closet seat ring and prevents contact therewith. The forwardly projecting portion of the sheet, forming the shield 19, is then folded downwardly on the folding line 17 and, thereafter, it covers and 110 protects the outer edge of the seat ring of the closet. When the loop 5 drops into the

closet bowl 23, it engages the water trapped in the bowl, so that when the flushing water is admitted to the bowl from the tank 25, it will forcibly engage the loop and draw the 5 protector cover into the bowl and convey it into the sewer, not shown.

Having fully described my invention, what I claim is—

1. A protector cover for toilet closet seats, 10 consisting of a rectangular sheet of moisture proof paper partially separated to form diagonally of the sheet a loop and within the loop a seat ring, said loop being provided with folding shoulders adapted to support 15 said seat ring and sustain said loop in operative position.

2. A protective cover for toilet closet seats, consisting of a rectangular sheet of moisture proof paper partially separated to form diagonally of the sheet a loop and within the 20 loop a seat ring, said loop being provided with folding shoulders adapted to support said seat ring and sustain said loop in operative position, a folding shield carried by the inner edge of said seat ring, and a forwardly 25 projecting folding portion adapted to shield the outer edge of said seat ring.

CLIFTON B. SLOAN.
